UNITED STATES PATENT OFFICE.

CHRIST PAPOUCHIS, OF FAR ROCKAWAY, NEW YORK.

GAME APPARATUS.

Application filed May 7, 1921. Serial No. 467,756.

To all whom it may concern:

Be it known that I, CHRIST PAPOUCHIS, a citizen of the United States, residing at 306 Central Avenue, Far Rockaway, New York, have invented certain new and useful Improvements in Game Apparatus, of which the following is a specification, reference being had to the accompanying drawings, forming a part hereof.

This invention relates to game apparatus in which the balls are bowled or rolled at a target and it has for its object generally to adapt such apparatus for use at places of public resort and to be used with great frequency without requiring the services of a special attendant. It aims to provide improved means whereby the score is indicated automatically, according to the relative value of the hits made. To provide means whereby the scoring devices can be reset at the end of a string or series of balls rolled there shall be concealed during the resetting, so as to prevent unfair manipulation by the player, means whereby a definite number of balls shall be released for the player. These and other features of improvement will be referred to more in detail herein-after. The several features of improvement are illustrated in the accompanying drawings as embodied in a suitable and convenient form of apparatus and in the drawings—

Figure 1 is a top view, more or less diagrammatic, illustrating generally the arrangement of the alley on which the balls are bowled and on which they are returned to the player.

Figure 2 is a view of the same in side elevation, also somewhat diagrammatic.

Figure 2^a is a diagrammatic view in section on the plane indicated by the line 2^a of Figure 2.

Figure 3 is a detail view in side elevation illustrating particularly the means whereby the player can release a definite number of balls and at the same time reset the scoring devices.

Figure 4 is a partial top view of the devices shown in Figure 3.

Figure 5 is a detail view partly in horizontal section indicated by the broken line 5—5 of Figure 3.

Figures 6 and 7 are detail views in vertical section respectively on the planes indicated on the broken lines 6—6 and 7—7 of Figure 3.

Figure 8 is a detail view of a portion of the target and scoring devices in horizontal section on the plane indicated by the broken line 8—8 of Figure 10.

Figure 9 is a view in front elevation, with parts broken away, of the target and scoring devices.

Figure 10 is a view of the same in side elevation, looking from the left hand in Figure 9, with the housing shown in section.

Figure 11 is a detail view in side elevation of the scoring and resetting devices shown in the upper part of Figures 9 and 10 as indicated by the broken line 11—11 of Figure 9, but on a larger scale.

Figure 12 is a detail view in front elevation of a portion of the resetting devices.

Figure 13 is a detail view in vertical section on the plane indicated by the broken line 13—13 of Figure 9.

Figure 14 is a detail view in section on the plane indicated by the arrow 14 in Figure 13.

Figure 15 is a detail view in section on the plane indicated by the broken line 15—15 of Figure 14.

Figure 16 is a detail view in rear elevation of parts indicated by the arrow 16 in Figure 11.

The form of alley in which the scoring and other features of the invention are preferably embodied, is sufficiently indicated in Figures 1, 2 and 2^a, the position of the player being indicated at *a* and the position of the target at *a'*. The floor of the alley on which the balls are rolled, as indicated at *a²*, is relatively narrow and is inclined, so that the balls are rolled by the player up hill from the player's stand *a* toward the target *a'*, the incline being preferably curved somewhat as shown, rather than straight. At each side of the narrow floor *a²* on which the balls must be rolled, is a trough *a³*, onto which the balls will fall if they are not properly directed by the player on the floor *a²* and into which the balls are directed from the target, the troughs *a³* being also inclined downwardly toward the player's stand so that the balls shall be returned by gravity to the player's stand.

At the player's end of one of the return troughs *a³*, preferably at the right hand side, is a compartment *b*, shown particularly in Figures 2, 3, 4, 6 and 7, into which may be admitted a definite number of balls and in which they are held by the hinged swinging side *b'* of the compartment with its

lower lip b^3 . When the swinging side or gate b' is released and swung, as indicated by broken lines in Figures 6 and 7, the balls drop into a lower compartment c , open at the top, as at c' in Figures 1 and 4, at a point beyond the top b^3 of the compartment b , so that the balls can be taken out by the player as required.

- 10 The gate b' of the compartment b can be operated to release the balls by any convenient means. In the construction shown the gate is operated by the movement of the same hand lever d which is used to reset the scoring devices, as hereinafter described.
- 15 This lever d , mounted on a pivot d' , co-operates with a bent, cam lever d^2 , which is pivoted on a vertical axis, as at d^3 and in turn coacts with an arm b^4 which is extended upwardly from the gate b' , so that as the lever d is pulled rearwardly by the player the lever d^2 is caused to act upon the arm b^4 to swing the gate b' and release the balls from the compartment b . The lever d may be coin controlled, as illustrated in Figures
- 20 3 and 5. The coin, indicated at e in Figure 5, is dropped into a chute e' and at the bottom thereof rests in the path of a pin e^2 carried by a spring arm e^3 , by which the pin is normally withdrawn. A spring pressed locking lever e^4 , pivoted at e^5 and forked at its end, as at e^6 , to stand normally in the path of movement of the lever d , but permitting limited initial movement therof, has at e^7 an aperture which registers with
- 25 the pin e^2 . The lever d carries a cam lever d^4 , to co-operate with the spring lever e^3 which carries the pin e^2 . The initial movement of the lever d is sufficient to press the pin e^2 toward the lever e^4 . If there is no coin in the chute e' , in the path of the pin e^2 , the lever e^4 is undisturbed by the movement of the pin e^2 , which passes freely through the opening e^7 , but if a coin, as at e , stands in the path of the pin e^2 , then the initial movement of the lever d causes the stop lever e^4 to be swung out of the path of further movement of the lever d and therefore permits the lever d to have its complete effective movement which, as already described, moves the gate b' to release the balls. The means by which the movement of the lever d effects the resetting of the scoring or indicating devices will be described hereinafter.
- 30 As there may be in the return trough a^3 more balls than should be released by the movement of the gate b' , there is provided a cut-off, operated by the movement of the gate to prevent the entrance of more than the proper number of balls into the compartment b . As shown particularly in Figures 3 and 7 the cut-off plate b^5 , pivoted at b^6 on an arm b^7 extended upwardly from the gate b' , and adapted to swing into position between the last ball in the compartment b and the next ball outside

of it, has a spring arm b^8 which bears against the gate b' , so that as the gate is opened, to release the balls the cut-off, which normally stands above the balls, is swung downwardly to prevent the entrance into the compartment b of other balls which may be in the trough a^3 .

In the target end of the alley is a board or wall f in which are three openings f' , f^2 , and f^3 , with corresponding openings a^4 , a^5 , and a^6 in the floor a^2 and communicating respectively with the openings f' , f^2 and f^3 . If a ball, rolled by the player, enters the central opening f^2 , a^5 it scores the maximum number of points, while if it enters either one of the side openings f' , a^4 or f^3 , a^6 , it scores a smaller number of points. If the ball enters the central opening f^2 , a^5 it falls directly upon a lever g which is hinged at g' . If the ball enters the opening f^3 , a^6 it falls directly upon a lever g^2 , which is pivoted at g^3 , is arranged transversely with respect to the levers g and is placed above the lever g so that compression of the lever g^2 will cause movement of the lever g but only through a fraction, preferably one-half, of the angular movement of the lever g when it is itself depressed by the falling of a ball upon it. A chute a^7 , shown by broken lines in Figure 9 directs the ball which enters the opening f' , a^4 toward the free end of the lever g^2 , which stands directly under the opening f^3 , a^6 , so that a ball which enters either of the two side openings acts upon the lever g^2 . A chute a^8 directs the ball which enters the central opening f^2 , a^5 upon the free end of the lever g . Since a ball which enters the central opening produces, for example, double the movement of the lever g , which is produced by a ball which enters either of the side openings and acts upon the lever g through the lever g^2 , the scoring or indicating mechanism may be actuated directly by the lever g alone, the movement of the scoring or indicating devices which is effected by a ball which enters the central opening being, for example, twice that which is effected by a ball which enters one of the side openings. The scoring or indicating mechanism will now be explained.

On a horizontal axis h , within the housing a^9 , is mounted a drum or reel or central frame h' in which are mounted to swing on separate axes h^2 ; number plates h^3 , which may be numbered consecutively zero, fifty, one hundred, one hundred and fifty, etc., up to and including one thousand. The reel is advanced one step, to release one number plate, by each ball which enters one of the side openings in the target, and is advanced two steps, to release two number plates, by each ball which enters the center opening in the target, the mechanism by which this is accomplished being described

hereinafter. Each number plate, as it is released, becomes visible to the player through a sight opening a^{10} in the housing a^9 . Each number plate falls into view by swinging 5 upon its own axis and the several number plates which are in readiness to be released are retained, until the carrier reel receives the movement by which each should be released, by a retainer i which may consist of 10 a plate pivoted to the supporting frame at i' and held yieldingly in position by a spring i'' .

One of the side members h^4 of the carrier reel is formed with ratchet teeth, as 15 shown in Figures 9, 10 and 11, and is adapted to be engaged by a spring pressed pawl h^5 which is carried by an arm h^6 , mounted on the axis h . One end of the pawl carrying arm h^6 may be connected, as by a chain 20 h^7 , with the lever g , as shown in Figure 10, and the pawl carrying arm may be suitably counter balanced, as by a spring or weight h^8 , to maintain the lever g , and the lever g^2 as well, in elevated position in readiness for 25 operation. When the carrier reel is advanced one step, by the means described, one number plate h^3 , will be released and fall into view and if the carrier reel is advanced two steps, two number plates will be released, the second of the two being visible 30 through the sight opening a^{10} . A stop pawl h^9 , shown in full lines in Figure 9 and in broken lines in Figures 10 and 11, may be provided to prevent reverse movement of 35 the carrier reel.

For the resetting of the indicating or scoring devices the carrier reel h' is rotated in a forward direction until the zero number plate has been released and exposed to view, 40 this operation being effected by the movement of the lever d above mentioned. As indicated in Figures 3, 10, 11 and 13, the lever d is connected by a wire h with a lever h' , the free end of which is connected by 45 a connector h^2 with one end of a lever h^3 , the other end of which is connected by a flexible and elastic connector h^4 with a drum h^5 . The latter is mounted on the axis h together with a second drum h^6 to which 50 may be connected, by a flexible connector h^7 a weight h^8 , wound in opposition to the connector h^4 for the purpose of restoring the drum h^5 , h^6 to normal position after operation. On the drum h^5 is mounted a spring 55 pressed pawl h^9 adapted to engage a lug h^{10} on the adjacent end of the carrier reel h' , so that the carrier reel shall be moved forwardly, until the zero number plate is exposed, by the movement of the lever d , the 60 pawl h^9 being so mounted as to permit the pawl and lug to pass each other when the carrier reel advances with respect to the drum or the drum is reversed with respect to the carrier reel.

65 In order that the player shall not, by ma-

nipulation of the lever d effect a partial movement of the scoring device so as to make his own score higher it is desirable that the number plates be concealed from view during movement of the carrier reel h' 70 by the operation of the lever d . Accordingly there is provided a shutter l , shown in Figures 9 and 10, which is carried by an arm l' secured to a short arm l^2 , shown also in Figures 11, 13 and 16, which is pivoted 75 to the frame at l^3 and normally is drawn rearwardly and downwardly, against a stop l^4 , by a spring l^5 , the shutter l being then held in its elevated position, as shown in Figure 10. The lever h^3 , which is moved in 80 the resetting operation, is armed with a lug h^{10} which, in the effective movement of the lever h^3 , co-acts with a spring pressed stop l^6 on the arm l^2 , and with the arm l^2 itself, thereby causing the arms l^2 and l' to be 85 moved from the position shown in full lines in Figure 10 to the position shown in broken lines, with the shutter l interposed between the sight opening a^{10} in the housing a^9 and the exposed number plate. As the lever h^3 90 completes its movement the lug h^{10} passes beyond the end of the arm l^2 and permits the arms l^2 and l' to be restored to their initial positions by the spring l^5 . Finally, 95 when the lever h^3 returns to its initial position the yielding stop l^6 permits the lug h^{10} to pass, as indicated in Figure 15. In order that the scoring reel h' , in the resetting operation, shall be stopped with certainty when the zero number plate is exposed there is 100 hung loosely on the axis h a stop arm m with which the spring pressed yielding pawl h^9 contacts when the reel has been moved to position to expose the zero number plate, the stop arm m then resting upon a fixed stop 105 m' . The stop arm, however, has limited capacity for upward swinging movement so that when the resetting drum is restored to initial position by its weight h^8 the pawl h^9 shall be moved slightly upward from its zero 110 position so as to be in position to engage the lug h^{10} on the carrier reel as soon as the reel is moved forward from its zero position through only one step.

115 It will now be understood that in the use of the improved game apparatus each ball bowled occasions a forward movement of the indicating or scoring mechanism through one step or two steps according to the value of the target opening entered by the ball, and that each ball is returned through the return chute a^2 to the player's position. When the player has bowled the full number of balls the number plate visible through the sight opening in the housing indicates 120 his full score. If the same player desires to bowl another string or if another player desires to bowl a string, the lever d is released upon the insertion of a coin, as described and is drawn back to its full extent, 125 130

thereby releasing the number of balls in the ball compartment and at the same time advancing the scoring mechanism until the zero number plate is shown at the sight opening, 5 the number plates being concealed during this resetting operation by the shutter.

It will be understood that various changes in details of construction and arrangement can be made and that the invention, except 10 as pointed out in the claims, is not limited to the precise construction and arrangement shown and described herein.

I claim as my invention:

1. The combination of an indicating device comprising a carrying reel and a plurality of number plates mounted thereon, a drum mounted on the same axis as the carrying reel but independently thereof and having a pawl for engagement with the reel, 15 means to rotate the drum in a forward direction to rotate the reel to its initial position and means to rotate the drum reversely to its initial position.
2. The combination of an indicating device comprising a carrying reel and a plurality of number plates mounted thereon, a drum mounted in the same axis as the carrying reel but independently thereof and having a pawl adapted to engage the reel to effect forward movement thereof with the 20 25 30

drum and to permit independent movement of the reel, means to rotate the drum in a forward direction to rotate the reel to its initial position and means to rotate the drum reversely to its initial position.

3. The combination of an indicating device comprising a carrying reel and a plurality of number plates mounted thereon, a drum mounted in the same axis as the carrying reel but independently thereof and having a pawl adapted to engage the reel to effect forward movement of the reel, means to rotate the drum in a forward direction to rotate the reel to its initial position, means to rotate the drum reversely to its initial position and means to check positively the forward movement of the drum in its initial position.

4. In a device as described having an indicating device, an arm carrying a shutter to conceal the indicating device during such continuous forward movement and actuated by said lever during its effective movement, said arm having a yielding stop to engage the lever when the latter is moving in one direction and to permit independent movement of the lever in the opposite direction.

This specification signed this 6th day of May, A. D. 1921.

CHRIST PAPOUCHIS.
